UNITED STATES PATENT OFFICE

PAUL MANZ, OF NEWARK, NEW JERSEY

AUTOMATIC TRAFFIC SIGNAL

Application filed April 11, 1927. Serial No. 182,713.

This invention relates to signaling devices and more particularly to such apparatus used to automatically control the flow of traffic on public highways.

5 It is well known that devices for similar purposes have been installed at the important street intersections of many of the larger towns and cities of the United States, but those already in operation are ordinarily 10 manually operable.

This feature entails the services of an operator for each apparatus, burdening the city with a great expense and in addition the periods of time for the "Go" and "Stop" signals are irregular and not in synchronism with adjacent devices so that the harmony of the entire system is affected.

It is therefore the main object of the invention to eliminate the foregoing disadvantages 20 by providing a signal tower that is automatically operated, reducing the cost of upkeep and directing the traffic more efficiently.

It is a further aim to produce a novel means for making and breaking electrical circuits 25 to control visible signals.

A still further characteristic is in the provision of means whereby the changing of the signals is perfectly timed so that all of the apparatus installed on a particular thoroughfare may be actuated simultaneously, controlling that entire traffic lane in unison.

Still another object is to provide auxiliary actuating means enabling manual control should the automatic mechanism temporarily fail.

These and several other objects, which will become more apparent as the description progresses, are attained by the novel construction, combination and arrangement of parts, hereinafter described and illustrated in the accompanying drawings, forming an important component of this disclosure, and in which:—

Figure 1 is a side elevational view of a traffic signal tower made in accordance with this invention.

Figure 2 is a like view of upper portion of the same showing the signals in reversed position.

Figure 3 is a diagrammatical view show-

ing the manner of wiring the various signals.

Figure 4 is an enlarged, fragmentary vertical sectional view showing the lower portion of the tower and its associated mechanism.

Figure 5 is a fragmentary side elevational view of the signal actuating means.

Figure 6 is a sectional view of the timing cam operating means taken on line 6—6 of Figure 4.

Figure 7 is a side elevational view of the speed reducing gear train as shown in Figure 4.

Figure 8 is a sectional view taken on line 8—8 of Figure 9.

Figure 9 is a transverse sectional view taken on line 9—9 of Figure 8.

Figure 10 is a fragmentary sectional view showing the connection between the rod and one of the spiders, drawn to an increased scale.

Figure 11 is an enlarged side elevational view of the shutter actuating mechanism.

In the drawing, the numeral 15 generally designates a cylindrical base foundation of cement or any other preferred material, rising from the ground at a street intersection or any location where the tower is to operate, the foundation being surrounded by a tubular base casing 16 having a door 17 hinged above the cement.

The top of the cement is covered by a circular floor 18 on which rests an electric motor 19, connected by a cable 20, passing through the base to a source of current and a housing 21 carrying a gear train 22 connected by a clutch 23 with the motor to drive a shaft 24.

A cover 25, over the casing 16, has a hollow column 26 rising centrally therefrom, on the top of which is fixed a rectangular signal head 27 provided with a door 28, the entire structure being held rigid by a rod 29 fixed to the cover and signal head and passing through the column adjacent the wall thereof.

Fixed on the shaft 24 is a timing cam 30, provided with opposite concentric surfaces 31 intermediate raised surfaces 32 and concentric surfaces 33 of greater radii than the elements 31 on which rest a roller 34 rotatably carried on a holder 35 having a slot 36

in its lower end, receptive of the shaft 24, the holder supports a rod 37 of square cross-section, extending upwardly through the column 26 and head 27.

Secured on the rod 37, in the column 26, is a plate 38 of non-conducting material provided with a spring contact 39 engageable with either of three contacts 40, 41 and 42 respectively, lower, intermediate and upper.

10 Fixed in the column 26, on a level with the door 28, is a transverse partition 43 to which is pivoted, a switch lever 44 connected by a link 45 to a pivoted cam 46, the latter engaging a roller 47 rotatably secured to the rod 37 by clamp members 48, so that should the motor or its associated mechanism fail to operate, the signals may be manually operated as will later be seen.

20 The head 27 consists of four walls 49 arranged in parallel at uniformly spaced distances from the rod 37, each wall having right angled outwardly extending elements 50 to meet the registering portion of the adjacent wall.

25 The head is divided into three vertical rows and fixed in the lower row, at right angles to the bent portions 50 of the walls, are four lamp housings 51 provided with electric lamps 52, the housings having one end 53 open for a purpose later apparent and being provided with lenses 54 and 55 respectively red and green.

30 Pivottally mounted between the bent portions 50 and the backs of the opposite lamp housings 51 are opposed reversible signs 56 and 57, blank on one side and respectively bearing legends "Go" and "Stop" on their other faces.

35 The head wall end of each sign has fixed thereon pinions 58 engaging racks 59 formed on the ends of arms 60 of a spider 61 slidable on the rod 37 and connected to it by a pin 62 engaged in a slot 63 in the rod.

40 Pressing against the lower wall 64 of the head 27 is one end of an expansion spring 65 encircling the rod 37, the other end abutting a collar 66 fast on the rod so that the hub of the spider 61 will normally rest on the upper end of a spacer 67, rising from the wall 64 and the roller 34 will contact the timing cam 30.

45 All of the lights of the lower row are connected by a wire 68 to the contact 40.

50 The central row consists of four centrally disposed lamp housings 69 provided with lamps 70 and amber lenses 71, the lamps being connected by a wire 72 to the contact 41.

55 The upper row is similar to the lower row, except that the color of the lenses are reversed, as are the legends on the signs, and is actuated by a spider 73 slidable on the rod 37 and connected the same as the spider 61, the spider 73 being spaced from the lower spider by a spring 74, the upper end of the rod 37 engaging a spacer 75 extending down-

wardly from the upper wall 76 of the head 27.

The lamps 77 and 78, respectively red and green, of the upper row are connected by a wire 79 to the contact 42.

60 Fixed on the wall 76 is a cap 80 supporting a lamp 81 over which is placed a globe 82.

65 Thus, in operation, through the motor 19, the cam 30 is rotated to change the signals as follows:—

70 As shown in Figures 4 and 8, the rod 37 is at its lowest point, when the roller 34 engages the cam surface 31 at which time the contact 39 is engaged with the contact 40 to light the lower row of lamps 54—55.

75 When the upper row is lit the corresponding legends are visible and the lower row is not lit and the corresponding signs are blank.

80 As the cam continues to rotate the roller 34 engages the surface 32, moving the rod 37 upwardly which action through the spring 74 raises the spider 73.

85 By this time the contact 39 disengages the contact 40 and engages the contact 41 extinguishing the lamps 77—78 and causing the amber or caution lamps 71 to glow.

90 At the same time the rack and pinion 59—58 rotate the upper set of signs to show their blank surfaces.

95 Continued rotation of the cam 30 causes the roller 34 to engage the surface 33 which action moves the rod 37 further up.

100 However the spider 73 which now contacts the spacer 75, remains stationary, but the spider 61 rises to actuate the lower signs 56—57 showing their legends reversely to the first, showing of the upper signs thus changing the flow of traffic.

105 Simultaneously, the contact 39 disengages the contact 41 and engages the contact 42, extinguishing the caution lamps 71 and lighting the lower set of lamps 54—55.

110 As the cam moves further the operation repeats at timed intervals and in perfect harmony.

115 It will be noted that should the mechanical operating means become out of order, the signals may be actuated by the handle 44 and cam 46.

120 Thus it may be seen that a traffic signal has been disclosed capable of mechanical or manual operation and which is so designed as to control the traffic on a particular thoroughfare simultaneously at all street intersections.

125 Having thus described my invention, what I claim as new and desire to secure by Letters Patent, is:—

130 In a traffic signal a hollow base structure, a hollow standard mounted on said base and a head including Stop and Go signals mounted on said standard, a rod in said standard, means operated in accordance with the longitudinal position of said rod to cause the exhibition of said "Stop" or "Go" signals, motor means in said base for reciprocating

said rod longitudinally, including a lost motion connection permitting reciprocation of said rod independently of said motor means and manually operated means cooperating with said rod for moving the latter as permitted by the lost motion connection to also operate the signals when the motor means is not in operation.

5 This specification signed and witnessed this
10 eighth day of April, 1927.

PAUL MANZ.
